(57) **CLAIM**

We claim the ornamental design for an incubator noise control support, as shown and described.

DESCRIPTION

FIG. 1 is perspective view of an embodiment of an incubator noise control support;

FIG. 2 is a front view thereof;

FIG. 3 is a top plan view thereof;

FIG. 4 is a bottom plan view thereof;

FIG. 5 is a back view thereof;

FIG. 6 is a right side view thereof;

FIG. 7 is a left side view thereof;

FIG. 8 is a perspective view of another embodiment of an incubator noise control support;

FIG. 9 is a front view thereof;

FIG. 10 is a top plan view thereof;

FIG. 11 is a bottom plan view thereof;

FIG. 12 is a back view thereof;

FIG. 13 is a right side view thereof; and,

FIG. 14 is a left side view thereof.

The broken lines depict portions of the incubator noise control support that form no part of the claimed design.
